UNITED STATES PATENT OFFICE.

FRANK LOMBARDO, OF BROOKLYN, NEW YORK, ASSIGNOR TO PERCY KENT COMPANY, A CORPORATION OF NEW YORK.

BAG-PRINTING MECHANISM.

Application filed July 26, 1920. Serial No. 399,067.

To all whom it may concern:

Be it known that I, FRANK LOMBARDO, a citizen of the United States, residing at the city of New York, in the borough of Brooklyn and State of New York, have invented 5 certain new and useful Improvements in Bag-Printing Mechanism, of which the following is a full, clear, and exact description.

My invention relates to the art of bag printing and making and has especial application to the manufacture of cloth bags. In making such bags it is common practice first run a web of cloth through a folding machine of the Elliott and Hall type, which 15 arranges the web in folds the length of a bag section, and then to cut the folded web transversely along the median line, thus producing twice as many folded bag sections as there are folds of material. These stacks of folded bag sections are then unfolded and run through a printing press and from the printing rolls they are taken by an automatic folder and again folded double ready for sewing. The edges of such bag sections are 20 not so even as they were directly after the cutting, and are more or less frayed and disarranged, particularly with coarse material, such as burlap or the like, with the result that the speed of the operators of the sewing 25 machines is considerably reduced by the necessity of arranging the edges of the folded bag section evenly together. It is a well known fact that unprinted bags direct from the cutting operation can be sewed considerably faster than can the printed and refolded bags.

An object of my invention is to provide a apparatus for printing and making the bags which will avoid the necessity of unfolding 40 the bag sections after the cutting operation, and will enable the folded sections to be sewed as they are cut.

Still other objects and advantages of my invention will appear from the following description.

In accordance with my invention I first print alternately upon opposite sides of a web of material at spaced intervals corresponding to the length of a bag section, and 50 I then fold the printed web upon itself at the middle of each bag section. Then I cut the folded web so as to separate the several folded bag sections, after which I sew the bag and then turn it inside out. The printed matter is first folded inside in the folded

pile but appears on the outside after the bag is turned.

As the printed legend usually appears on one side only of a finished bag, I will ordinarily print only upon every second half bag 60 section, leaving a blank half section between each printed half section, and every printed half section will have its inscription upon the side of the web opposite to that of the inscription immediately preceding and following it. 65

In order to minimize waste in cutting I prefer to fold the printed webs in lengths equal to a bag section, thereby permitting the folded pile to be cut transversely through 70 the middle to separate the folded bag sections.

My invention also comprehends two reversely arranged printing couples in tandem and constructed so that, as the web is run 75 through them, one will print every other bag section upon one side and the other will print the intermediate bag sections upon the opposite side. I have found a press of the construction illustrated to be satisfactory, in 80 which the couples are spaced a distance equal to the length of a bag section and the printing cylinder has a peripheral length equal to the length of a bag section, while the impression cylinder is of double the diameter 85 of the printing cylinder. Since in most cases the inscription appears upon one side only of the finished bag, I have shown the printing plate as occupying one half of the circumference of the printing cylinder. In 90 order to accommodate a plate occupying the entire surface of the printing cylinder, I have shown the impression surface as one half of the circumference of the impression cylinder, though only one quarter of the circumference serves as an impression surface 95 in the arrangement illustrated. The construction of impression cylinder shown also provides better balance.

With such a press it is manifest that each 100 printing couple will print upon every fourth half bag section, the printed half sections alternating with blank half sections and the alternate ones being printed on opposite sides of the material.

The folding mechanism may be part of the press or the printed web may be run on to a roll or otherwise disposed of and subsequently run through a suitable folder to fold it into the proper lengths for cutting. If 110

the speed of the press is not too rapid for accurately folding into the relatively short lengths, the web will be folded into the proper lengths for cutting as it comes from 5 the printing rolls.

I shall now describe the apparatus shown in the accompanying drawings, but it will be understood that this is merely illustrative and that modifications may be made therein 10 without departing from the scope of the appended claims.

Fig. 1 is an elevation of the apparatus;

Fig. 2 is a diagrammatic representation in 15 sectional elevation of the parts necessary to illustrate the operation of the apparatus;

Fig. 3 is a diagrammatic representation in plan of the parts illustrated in Fig. 2;

Fig. 4 is a side elevation, more or less diagrammatic in character, of a folded pile of 20 material after being cut, and a suitable truck or conveyer for the same;

Fig. 5 is a transverse section of a bag after being sewed;

Fig. 6 is a plan of the same before turning, 25 and

Fig. 7 is a plan of the same after turning.

Power is supplied to the illustrated apparatus from a pulley 1 on a counter shaft 2. The rotation is imparted to the cylinders 30 of the printing couples from a pulley 3 driven by belt 4 from pulley 1. The first printing couple consists of the printing cylinder 5 and the impression cylinder 6, and the second printing couple consists of the 35 printing cylinder 7 and the impression cylinder 8. The first couple is arranged to print upon the top of the web and the second couple is arranged to print upon the bottom of the web. The two couples are 40 driven continuously at the same speed and in the same direction, as indicated by the arrows in Fig. 1, through suitable gearing. The ratio of the diameter of the printing cylinder to the impression cylinder in each 45 couple is 1:2, one-half of the surface of the impression cylinders being arranged as an impression surface, while the printing plates couple is 1:2, one-half of the surface of the printing cylinders. The printing couples together with the drive pulley 3 with its shaft 50 and connecting gearing are supported on a suitable frame 9. The printing couples are spaced apart a distance equal to the length of a section of the web from which a bag 55 will be made when the web is cut up and which I term a bag section.

The web 10 is drawn from a bale or pile on a truck 11 and passes first through feeding rollers 12 supported on a stanchion 13 60 and driven by a belt 14 from pulley 1. Thence it passes over a pan 15, also supported on the stanchion 13, thence over a guide board 16 and idler roller 17, thence under an idler roller 18, and thence through 65 the two printing couples. In this way, as

the web passes through the press it is printed on its top side at intervals equivalent to every fourth half bag section, and it is also printed on its underside at corresponding intervals and on half bag sections intermediate 70 those printed on the top side.

For example, the first half bag section at the leading end of the web will receive an imprint on its top side, the next half bag section will be blank, the next half bag section will be 75 printed by the second couple on its bottom side, the next half bag section will be blank, the next half bag section will be printed again by the first printing couple, and so on.

I have shown in the illustrated mechanism means for folding the web as it is printed and it will be understood that these folds may or may not correspond in length with a bag section. If they do not so correspond, then the printed web will be run through a folding machine of the Elliott and Hall type for the purpose of folding them to the proper length. From the advance printing couple the web passes over an idler 19 and thence over a tension roll 20 the surface of which is provided with pins and which is driven by a sprocket chain 21 which connects a sprocket wheel 22 on the tension roll 20 with a sprocket wheel 23 on the printing cylinder 95 7. From the tension roll 20 the web passes underneath an idler roll 24 and thence upward over an idler roll 25 supported on a stanchion 26 and thence through feed rolls 27 also supported on the stanchion 26 and 100 driven by belt 28 from pulley 1. From the feed rolls 27 the web passes downward through the oscillating member 29 of the folding mechanism. This oscillating member is pivoted to swing on the shaft of the lower feed roller 27 and has two spaced 105 guide plates between which the web passes. The oscillating member 29 is oscillated by a crank 30 which is arranged on a transverse shaft 31 having its bearings in depending arms from the stanchion 26, and the crank is connected to the oscillating member 29 by means of the connecting rod 32. The crank shaft 31 is driven by a pulley 33 which is connected by a belt 34 to a pulley 35 on the 110 shaft of the lower feed roll 27. The length of the fold will be regulated by the length of the oscillating member 29 and the frequency of the oscillating movement will be regulated to take care of the web as it is 115 fed to the folding mechanism.

When the final folding operation is completed the pile will be arranged as shown in Fig. 4, after which it will be cut transversely through the center, as shown, thus 125 dividing the folded pile into two piles of folded bag sections 36 with the printed inscription on the inside of the lower half of each bag section. This printed inscription is indicated in Fig. 4 by the dotted lines. 130

It will be observed that in the pile illustrated the leading half bag section was printed on its top, the next half bag section was left blank, the next half bag section was printed 5 on its bottom, the next half bag section was left blank, the next half bag section was again printed on the top, and so on. In the folding this brings the bag sections with the printing arranged as above described.

10 The cut edges are now perfectly true and even and the bags now pass through the sewing operation without being again disturbed.

15 In Fig. 5 is illustrated in transverse section a bag after it has been sewed. In order to prevent fraying or raveling along the cut edge it is customary to turn the two raw edges back and sew through the four thicknesses of material as illustrated. It is unnecessary to do this along the end since that 20 edge is not a raw edge. When the sewing operation is completed the bag appears as shown in Fig. 6, after which it is turned inside out, thus bringing the seams on the inside and the printed inscription on the 25 outside.

I claim:

1. A bag printing machine comprising two rotary printing couples spaced apart substantially the length of a bag section and 30 arranged to print upon opposite sides of a web, the periphery of the printing cylinder of each couple being substantially equal to the length of a bag section and the co-operative impression cylinder having a diameter twice that of the printing cylinder and having an impression surface for no more than half of its circumference, and means 35 for feeding a web through the couples, whereby the couples print upon opposite sides of alternate bag sections of the web.

40 2. A bag printing machine comprising two printing couples arranged to print upon

opposite sides of a web, means for feeding a web through the two couples, means for bringing the printing couples into printing 45 relation with alternate bag sections of the web, and means for folding the printed web upon itself at the middle of each bag section.

3. A bag printing machine comprising two printing couples arranged to print 50 upon opposite sides of a web, means for feeding a web through the two couples, means for bringing one couple into printing relation with every fourth half bag section of the web, means for bringing the other 55 couple into printing relation with every fourth half bag section of the web intermediate those printed by the first couple, and means for folding the printed web upon itself at the middle of each bag section in 60 folds substantially the length of a bag section.

4. A bag printing machine comprising two rotary printing couples spaced apart substantially the length of a bag section and 65 arranged to print upon opposite sides of a web, the periphery of the printing cylinder of each couple being substantially equal to the length of a bag section and the co-operative impression cylinder having a diameter twice that of the printing cylinder and having an impression surface for no more than half of its circumference, means 70 for feeding a web through the couples, whereby the couples print upon opposite sides of alternate bag sections of the web, and means for folding the printed web upon itself at the middle of each bag section in 75 folds substantially the length of a bag section.

80 In witness whereof, I hereunto subscribe my signature.

FRANK LOMBARDO.
